UNITED STATES PATENT OFFICE.

JOHN A. GILMAN, OF AMERICAN LAKE, WASHINGTON.

EXCAVATOR.

1,424,093.

Specification of Letters Patent. Patented July 25, 1922.

Application filed September 4, 1920. Serial No. 408,202.

To all whom it may concern:

Be it known that I, JOHN A. GILMAN, a citizen of the United States, residing at American Lake, in the county of Pierce and 5 State of Washington, have invented new and useful Improvements in Excavators, of which the following is a specification.

This invention relates to excavating machines and it consists in the novel features 10 hereinafter described and claimed.

An object of the invention is to provide a machine of the character stated having means for breaking the soil, soft rock or similar material and for passing the broken 15 particles back upon a conveyor from which the material is delivered into a receptacle and from the receptacle the said material is elevated and deposited upon a second conveyor which is adapted to carry the same 20 to one side of the trench and deposit it upon the surface of the ground.

With this object in view the excavator comprises a wheel mounted frame with a motor for propelling the same. A steering 25 device is provided for guiding the wheel to which the propelling power from the motor is applied.

The machine is provided at its forward 30 end with a cutting or disintegrating device adapted to be adjusted vertically and which includes picks or tools adapted to engage the solid material and break the same into particles which are carried back and deposited upon the first mentioned conveyor. 35 Means are provided for operating the said conveyor from the motor and other means are provided for operating the elevator from the motor. The second mentioned conveyor is operated from means which are included 40 in the elevator operating means.

In the accompanying drawings:—

Figure 1 is a side elevation of the forward portion of the excavator.

Figure 2 is a similar view of the rear 45 portion of the same.

Figure 3 is a detail side elevation of a rear portion of the excavator with parts in section.

Figure 4 is a plan view of the rear portion 50 of the excavator with parts broken away and parts in section.

Figure 5 is a plan view of the forward

portion of the excavator with parts broken away and parts in section.

Figure 6 is a transverse sectional view 55 through the forward portion of the excavator.

Figure 7 is a transverse sectional view through the steering wheel of the excavator.

Figure 8 is a plan view of the forward 60 portion of the excavator.

Figure 9 is a similar view of the rear portion of the excavator.

Figure 10 is an elevation of the rear portion 65 of the excavator.

Figure 11 is a horizontal sectional view through an elevating and levelling mechanism used upon the machine.

Figure 12 is a perspective view of a pick 70 arm used on the excavating machine.

The excavator comprises a frame 1 of metal and of any suitable design and which is provided at its forward end with downwardly and forwardly inclined brackets 2.

The brackets 2 are mounted upon a cross bar 75 3 which is mounted for sliding movement transversely of the frame. Means hereinafter described is provided for sliding the said bar with relation to the frame. A shaft

4 is journaled for rotation at the forward 80 portions of the brackets 2 and carries a series of radially disposed arms 5. A worm wheel 6 is fixed to the shaft 4 and a worm 7 meshes with the said worm wheel. The worm 7 is carried by a shaft section 8 best

shown in Figure 1 of the drawings. Staffs 9 are pivotally connected at the outer ends of the arms 5 and the said staffs carry at 85 their outer ends picks 10 of suitable pattern. Brackets 11 are mounted for vertical adjustment at the forward portion of the frame 1 and wheels 12 are journaled in the lower portions of the said brackets 11.

The brackets 11 may be adjusted vertically 90 with relation to the frame 1 by means of screws 13 which are provided at their upper ends with hand wheels 14. Guides 15 are mounted at the forward portion of the frame 1 and arcuate members 16 are slidably mounted in the guides 15 and provided at

100 the upper portions of their rear edges with teeth 17. The upper parts of the members 16 are guided in arms 18 which are carried by standards 19 mounted on the forward

portion of the frame 1, and which serve in part as means for guiding the vertical movement of the brackets 11 hereinbefore described. A scraper 20 is carried by the 5 arcuate members 16 and may be raised and lowered with the same. Deflector plates 21, 22 and 23 are interposed between the scraper 20 and the frame 1 and may move with relation to each other whereby the brackets 10 2 may move transversely of the frame 1. The plate 21 is connected with a stationary part of the apparatus, plate 23 is connected with the scraper 20, while the central plate 22 is loosely arranged so that the plates can 15 have sliding movement on each other to permit movement of the scraper. A shaft 24 is journaled upon the frame 1 and carries gear wheels 25 which mesh with the teeth 17 of the arcuate members 16.

20 It is apparent that when the shaft 24 is rotated the gear wheels 25 which are in mesh with the teeth 17 move the arcuate members 16 through the arms 18 and their connections with the frame 1 whereby the scraper 20 is 25 raised and lowered and inasmuch as the deflectors 21, 22, and 23 overlap each other they move with relation to each other to permit of the vertical adjustment of the scraper.

An engine 26 is mounted upon the frame 30 1 and its shaft 27 is provided with a gear 28 which engages an idle wheel 29 which in turn engages a pinion 29' mounted on a shaft 30 journaled upon the frame 1. At its forward end the shaft 30 is connected by 35 means of a universal joint 31 with a stub shaft 32 which is slidably received in a sleeve 34 connected by means of a universal joint 33 with the shaft section 3. Consequently it will be seen that means are provided for rotating the shaft 4 from the shaft of the engine 26 to cause the picks 10 to move about the axis of the shaft 4 and engage the earth as the machine moves along a trench or excavation. Shaft 27 is also 40 connected by worm gears to a shaft 27' and this shaft is connected by worm gears to a crank shaft 27", the crank of which is connected by a link 38 with a part of the cross bar 3 so that said bar will be given its trans- 45 verse sliding movement when the engine is in operation. It will thus be seen that the brackets 2 will be reciprocated transversely as the picks are being rotated so as to cause said picks to engage all parts of the front 50 wall of the trench being dug and this transverse movement will cause the picks to make the trench wide enough to provide ample room for the apparatus. This movement also permits the pick carrying members to 55 be spaced apart as each pick will operate over a stretch of wall considerably wider than itself.

Hangers 35 depend from the sides of the intermediate portion of the frame 1 and a roller 36 is journaled between the said hang- 60 ers. Arms 37 are pivotally connected with the shaft of the roller 36 and at their ends the said arms carry a roller 38 which is located behind the scraper 20. A belt 39 is trained around the rollers 36 and 38 and a 70 tensioning device 40 is mounted upon the arms 37 and engages the lower run of the belt 39 to maintain the upper run thereof at a proper degree of tension. A pulley 41 is mounted upon the shaft 41' of the roller 75 36 and a pulley 42 is driven from the shaft 30. A belt 43 is trained around the pulleys 41 and 42 and is adapted to transmit rotary movement from the engine to the shaft of the roller 36. Pulley 42 is carried by a shaft 42' 80 which is connected by the worm gear 42" with the shaft 30. Consequently means are provided for moving the belt 39 longitudinally. When the material is dug and cast up by the scraper 20 and directed by the deflector plates 21, 22 and 23 upon the upper run of the belt 39 the said upper run moving in an upward direction carries the material up toward the rear end of the frame 1 and constitutes the primary conveyor of 85 the machine.

A receptacle 44 is hung under the intermediate portion of the frame 1 and is adapted to receive the material from the upper run of the belt 39. Standards 45 are mounted 90 upon the intermediate portion of the frame 1 and cross bars 46 connect the standards 45 at the same side of the machine together.

A shaft 47 is journaled below the frame 1 100 at a point between the ends of the receptacle 44 and carries sprocket wheels 48. Chains 49 are trained around the wheels 48 and also around wheels 50 mounted upon a shaft 51 which is journaled upon the bars 46. Buckets 52 are carried by the chains 49 and are adapted to receive the material which is deposited in the receptacle 44 and elevate the same and carry it over the shaft 51. A bevelled gear wheel 53 is fixed to the side of one 105 of the wheels 50 and a shaft 54 is journaled for rotation in bearings mounted upon the bars 46. A sleeve 56 is slidably mounted upon the shaft 54 but is constrained to rotate in unison with the same and the said sleeve carries bevelled pinions 57 which are adapted to be moved in engagement, at different times with the teeth of the wheel 53. A bevelled gear wheel 58 is fixed to the forward 110 end of the shaft 54 and meshes with a bevelled pinion 59 mounted at the upper end of a vertically disposed shaft 60. A bevelled pinion 61 is carried at the lower end of the shaft 60 and meshes with a similar pinion 62 mounted on a shaft 63 which carries at 115 its forward end a gear wheel 64 which meshes with a gear wheel 65 mounted on the shaft 30 as best shown in Figure 9 of the drawing.

Consequently means are provided for re- 120

tating the shaft 63 from the shaft of the engine 26 and by the intermeshing pinions 62 and 61 the shaft 60 is rotated and through the intermeshing parts 59 and 58 the shaft 54 is rotated and inasmuch as one of the pinions 57 is in engagement with the gear wheel 53 the shaft 51 is rotated and consequently the chains 49 and buckets 52 are moved about the wheels 48 and 53. A bell 10 crank lever 66 is pivoted upon one of the bars 46 and engages the inner sleeve 56. A bell crank lever 67 is pivoted upon the rear standards 45 and the said bell crank levers are connected together by means of a rod 15 68. A rod 69 is connected at its rear end with the lower arm of the bell crank lever 67 and the forward portion of the rod 69 is connected with a lever 70 which is mounted at the forward part of the machine. Consequently 20 it will be seen that by turning the lever 70 the rod 69 is moved longitudinally whereby the bell crank lever 67 is swung and the rod 68 is moved vertically thus swinging the bell crank lever 66 which in 25 turn will move the sleeve 56 upon the shaft 54 whereby one or the other of the wheels 57 may be brought into mesh with the teeth of the wheel 53.

The shaft 63 hereinbefore described is 30 connected with a shaft 71 by means of a universal joint 72. A spindle 73 is journaled for rotation at the rear portion of the frame 1 and carries at its upper end a gear wheel 74. The spindle 73 carries at 35 its lower end a bracket 75 in which a wheel 76 is journaled. The said wheel 76 is adapted to travel along the bottom of the trench or excavation which is opened up by the machine. A beveled gear wheel 77 is journaled to the upper portion of the spindle 73 and is connected with a frame 78 which in turn is provided with an anti-friction bearing 79 in the form of balls as shown in Figure 4 which are interposed between the 40 said frame 78 and the frame 1. A shaft 80 is journaled in the frame 78 and carries at its lower end a beveled pinion 81 which meshes with a similar pinion 82 attached to the axis of the wheel 76 hereinbefore described. A sprocket wheel 83 is carried at 45 the upper portion of the shaft 80 and a similar wheel 84 is fixed to the wheel 77 hereinbefore described. A sprocket chain 85 is trained around the wheels 84 and 83 and 50 is adapted to transmit rotary movement from the wheels 77 to the wheel 76. In view of the fact that the wheel 76 is the steering wheel of the machine it will be seen that the said wheel is also the positively driven 55 wheel. A shaft 86 is journaled upon the frame 1 and carries at its rear end a worm 87 which meshes with the wheel 74. As the shaft 86 is rotated the rotary movement is transmitted through the worm 87 and the 60 wheel 74 to the spindle 73 and consequently 65 the wheel 76 is steered. The shaft 86 is connected by means of a universal joint 88 with a shaft 89 which is journaled at the side of the frame 1 and the forward end of the shaft 89 is operatively connected with 70 a steering device 90 best shown in Figure 8 of the drawing.

A shaft 91 is journaled for rotation at the rear portion of the frame 1 and is operatively connected with the shaft 71 by intermeshing beveled pinions 92 and 93 shown in Figure 4 of the drawing. The shaft 91 carries at its rear end a friction disk 94 and a disk 95 is arranged to move across the face of the disk 94. The disk 95 is 75 slidably mounted upon a shaft 96 which is journaled upon the rear portion of the frame. A lever 97 is connected with the disk 95 and a rod 98 is connected at its rear end with the said lever 97. The forward end 80 of the rod 98 is operatively connected with a lever 99 which may be swung for moving the rod 98 longitudinally. As the said rod 98 is moved the lever 97 is swung whereby the disk 95 is carried across the face of 85 the disk 94 and the motion which is transmitted from the shaft 91 to the shaft 96 may be increased or diminished or reversed according to the side of the axis of the shaft 91 at which the disk 95 is positioned. A gear wheel 100 is carried by the shaft 96 and meshes with a gear wheel 101 mounted on a stub shaft 102 journaled upon the rear portion of the frame 1. A beveled gear 90 103 is mounted upon the stub shaft 102 and meshes with a similar gear wheel 104 loosely mounted upon a shaft 105 journaled at the rear portion of the frame 1. A gear wheel 106 is fixed upon the shaft 105 and 100 meshes with the teeth of the wheel 77 hereinbefore described. A clutch member 107 is slidably mounted upon the shaft 105 and may be moved into engagement with the hub of the wheel 106 to fix the said wheel 106 with relation to the shaft 105. A bell 105 crank lever 108 is mounted upon the rear portion of the frame 1 and one arm of the said lever 108 is operatively connected by means of a link 109 with the clutch member 107. A rod 110 is connected at its rear end 110 with the bell crank lever 108 and the forward end of the rod 110 is connected with a lever 111 pivoted at the forward portion of the frame 1. Consequently it will be seen that when the lever 111 is swung to 115 move the rod 110 longitudinally the bell crank 108 is swung whereby the clutch member 107 is moved into or out of engagement with the hub of the wheel 106. When the said clutch member is in engagement with the hub of the wheel 106 rotary movement is transmitted from the shaft 91 through the friction disks 94, 95, shaft 96, intermeshing gear wheels 100 and 101 and the 120 wheels 103 and 104 to the shaft 105 and the 125 130

wheel 77. Inasmuch as the wheel 77 is operatively connected with the shaft 80 which in turn is operatively connected with the axis of the steering wheel the said steering 5 wheel is propelled irrespective of the direction in which it may be disposed for guiding the movement of the machine.

As the machine cuts an excavation or a trench the material is elevated as hereinbefore described and deposited upon a conveyor 112 located at the rear portion of the frame 1. This conveyor is operatively connected by means of a chain 113 with the shaft 54 hereinbefore described and therefore 10 the material which is deposited upon the conveyor 112 is carried to one side or the other of the excavations and deposited upon the surface of the ground.

From the foregoing description taken in conjunction with the accompanying drawing it will be seen that an excavator of simple and durable structure is provided and that the same includes means for shifting the cutting devices transversely with relation to the frame of the machine, also means for raising and lowering the forward portion of the frame of the machine with relation to the cutting devices, also means for carrying the excavated material rearwardly 15 and elevating the same and depositing it upon a conveyor adapted to carry the material beyond the side of the trench or excavation and deposit the same at the surface of the ground or in wagons. Furthermore 20 the machine includes means for steering the dirigible wheel which supports the rear portion thereof and consequently the machine may be used in places where space is limited and where it is desired to accurately direct the machine during the course 25 of cutting an excavation or trench.

Having described the invention what is claimed is:—

1. An excavator comprising a supporting frame, a bracket mounted upon the frame, means for moving the bracket transversely of the frame, a plurality of sets of cutters carried by the bracket, the sets being spaced apart and means for operating the cutters.
2. An excavator comprising a wheel mounted frame, a bracket mounted for movement transversely of the frame, means for moving the bracket, cutters carried by the bracket, means mounted upon the frame

for operating the cutters, and means for raising and lowering the forward portion of the frame with relation to the cutters.

3. An excavator comprising a wheel mounted frame, brackets mounted upon the frame, means for moving the brackets transversely of the frame, cutters carried by the brackets, means mounted upon the frame for operating the cutters, means for raising and lowering the forward portion of the frame with relation to the cutters and deflector plates connected with the brackets and frame and movable with relation to each other.

4. An excavating machine comprising a wheel mounted frame, means carried at the forward portion of the frame for cutting material and for casting the same rearwardly, a conveyor adapted to receive the said material, an elevator adapted to receive the material from the conveyor, means mounted upon the frame for operating the cutters, conveyor and elevator, and a second conveyor adapted to receive the material from the elevator and adapted to swing with relation to the same to deposit the material at the surface of the ground beyond either side of the machine.

5. An excavator comprising a wheeled frame, a bracket mounted upon the frame, means for moving the bracket transversely of the frame, a shaft carried by the bracket, means for rotating the same, a plurality of sets of arms connected with the shaft, said sets being spaced apart and picks carried by the arms.

6. An excavator comprising a wheeled frame, a bracket mounted upon the frame, means for moving the bracket transversely of the frame, a shaft carried by the bracket, means for rotating the same, a plurality of sets of arms connected with the shaft, said sets being spaced apart, picks carried by the arms, said picks being pivotally connected with the arms.

7. An excavator comprising a wheeled frame, a bracket mounted thereon, means for moving the bracket transversely of the frame, a plurality of cutters carried by the bracket, means for actuating the cutters, a scraper associated with the cutters and means for adjusting the scraper vertically.

In testimony whereof I affix my signature.
JOHN A. GILMAN.
